MUZZLE FOR A SPEAR FISHING GUN

James S. Christiansen, 135 Covina, Long Beach, Calif.

Filed May 28, 1959, Ser. No. 56,115

Term of patent 14 years

(Cl. D30—1)

Figure 1 is a perspective view of a muzzle for a spear fishing gun showing my new design;

Fig. 2 is a rear elevational view thereof;

Fig. 3 is a side elevational view; and

Fig. 4 is a top plan view thereof.

The broken lines of Fig. 1 are for purposes of illustration only.

I claim:

The ornamental design for a muzzle for a spear fishing gun, substantially as shown and described.
